DESIGN FOR A POCKET PENCIL OR SIMILAR ARTICLE

Sylvester G. Lipic, St. Louis, Mo.

Application December 14, 1939, Serial No. 88,890

Term of patent 14 years

To all whom it may concern:

Be it known that I, Sylvester G. Lipic, a citizen of the United States, residing in the city of St. Louis and State of Missouri, have invented a new, original, and ornamental Design for a Pocket Pencil or Similar Article, of which the following is a specification, reference being had to the accompanying drawing, forming part thereof.

The figure is an elevational view of a pocket pencil, showing my new design.

The distinguishing feature of this invention resides in the transparent top portion of the pencil as shown extending above the clip and containing a liquid of a color contrasting with that of the body of the pencil.

I claim:

The ornamental design for a pocket pencil or similar article, as shown and described.

SYLVESTER G. LIPIC.
